W. S. JOSEPHSON

THERMOSTATIC VALVE FOR REFRIGERATING APPARATUS

Filed April 26, 1923

UNITED STATES PATENT OFFICE.

WALTER S. JOSEPHSON, OF LONG ISLAND CITY, NEW YORK, ASSIGNEE TO B. M. J. UTILITIES, INC., OF NEW YORK, N. Y., A CORPORATION OF NEW YORK.

THERMOSTATIC VALVE FOR REFRIGERATING APPARATUS.

Application filed April 26, 1923. Serial No. 634,787.

To all whom it may concern:

Be it known that I, WALTER S. JOSEPHSON, a citizen of the United States, residing at Long Island City, in the county of Queens and State of New York, have invented a new and useful Thermostatic Valve for Refrigerating Apparatus, of which the following is a specification.

The object of my invention is to provide an improved thermostatically regulated valve for attachment to a container of a gaseous substance which has been reduced to a liquid state, such as a standard container of liquid carbon dioxide, whereby the use of such a liquid as a refrigerant may be more efficiently accomplished. It is also my object to provide the novel combination of a coil in connection with such a valve and a container of a gaseous substance which has been reduced to a liquid state; and to provide the novel combination and arrangement of parts disclosed in the accompanying drawings, in which--

Figure 1 is a side elevation of my invention applied to a container of liquid carbon dioxide, the hand wheel controlling the valve of the container being shown in section to illustrate the mode of attaching the new device to a standard container;

Fig. 2 is an enlarged longitudinal sectional view of my device; and

Fig. 3 is a side elevation of a modified form of my invention in which the refrigerating coil is interposed between the aforesaid container and the nozzle, whereby to extend the area of refrigeration.

Like numerals indicate like parts in each of the several views.

Referring to the accompanying drawings, I provide a standard liquid carbon dioxide container 1, having the usual valve stem 2, hexagonal head 3 of the valve stem, hand wheel 4 mounted on and controlling head 3 of the valve stem, and the usual outlet 5 in the valve stem 2. I provide a nozzle 8, having a threaded end 7 and a suitable nut portion 14 adapted to be engaged by the wrench for readily attaching it to or removing it from the interiorly threaded valve head 3. Nozzle 8 is provided with a bore 9, which is gradually tapered up to a point 10, from which point there is provided the flared outlet 11. I provide suitable small channels 12 opening into the bore 9 at its narrowest

point 10, said channels 12 being diagonally disposed, as shown in Fig. 2. I also provide similar channels 13 suitably disposed at a point rearward of the channels 12 and opening into the bore 9, as shown in Fig. 2. These channels preferably are arranged in a staggered relation. The numeral 15 designates a cone or plug of ice which will form in and shut off the flow of refrigerant through the nozzle 8 when the temperature of the gas container descends below the freezing point.

Referring to Fig. 3, I interpose between the nozzle 8 and the refrigerant container 1 a refrigerating coil 18, the end pipe portion 19 of which is suitably attached, as by a union 16, to the end of the refrigerant container 1, while the other end 19 of the coil is suitably attached, as by a union 20, to the threaded end 7 of my nozzle 8.

In operation, the refrigerant flowing through the bore 9 of nozzle 8 sucks in air through the channels 12 and 13, preventing the freezing of the refrigerant in the outlet 11 and permitting of the plug of ice 15 to form in the bore back of the point 10 only after the temperature of the chamber into which the gas container is placed falls below the freezing point. The refrigerant used in this container, which is carbon dioxide, is heavier than air and, therefore, a given velocity more quickly overcomes pressure per square inch or takes the position of water flowing through an injector past open passages to a pressure as high as the pressure which supplies the energy. In other words, the velocity of the refrigerant will carry it through the bore 9 and outlet 11, sucking in air through the channels 12 and 13 so that the gas flowing through the outlet 11 is mingled with air.

The plug of ice 15 alternately forms, closing the bore 9, and then melts again, releasing the flow of carbon dioxide to renew its function as a refrigerant, whereby the nozzle 8 functions automatically as a thermostatic valve.

What I claim is:

1. In combination with a container of a refrigerant of the class described, a nozzle detachably secured to said container, said nozzle having a tapered bore extending through the major portion of the nozzle, said bore terminating in a short flared out-

- let, the nozzle having air passages opening into the bore at approximately its narrowest portion.
2. In combination with a container of a refrigerant of the class described, a nozzle detachably secured to said container, said nozzle having a tapered bore extending through the major portion of the nozzle, said bore terminating in a short flared out-
- 10 let, the nozzle having air passages opening into the bore at approximately its narrowest portion, and a plurality of diagonally arranged air passages opening into the bore at its narrowest portion and at portions
- 15 slightly back of the narrowest portion of the bore, said passages being diagonally disposed relative to the bore.
3. In a device of the class described, the combination of a detachable nozzle having
- 20 a restricted passage therethrough, the most restricted portion of the passage being farthest from the point where the refrigerant enters the nozzle, the nozzle having di-
- agonally arranged air passages opening into the aforesaid passage at the aforesaid restricted portion, a container for carbon dioxide under high pressure, and a refrigerating coil having one of its ends detachably connected to the container and having its other end detachably connected to the afore- 25 said nozzle.
4. The combination of a container for carbon dioxide under high pressure, a refrigerating coil detachably connected to said container, a nozzle detachably connected to the refrigerating coil, said nozzle having a tapered bore therethrough, and having a flared outlet, the nozzle also having diagonal channels positioned to open into the bore at approximately its most restricted portion, 30 substantially as and for the purpose of controlling the flow of refrigerant and increasing the efficiency of the device as a refrigerating means.

WALTER S. JOSEPHSON.
